UNITED STATES PATENT OFFICE

FRITZ SCHULTE, OF HILLSIDE, NEW JERSEY, ASSIGNOR TO W. C. EDGE JEWELRY CO.,
OF NEWARK, NEW JERSEY, A CORPORATION OF NEW JERSEY

DESIGN FOR A PENDANT

Application filed July 16, 1930. Serial No. 36,373. Term of patent 3½ years.

To all whom it may concern:

Be it known that I, FRITZ SCHULTE, a citizen of the United States, residing at Hillside, in the county of Union and State of New Jersey, have invented a new, original, and ornamental Design for Pendant, of which the following is a specification, reference being had to the accompanying drawings, forming part thereof.

In said drawings, Figure 1 is a front face view, Figure 2 is a top edge view, and Fig. 3 is a rear face view of the pendant, showing my new design.

I claim:—

The ornamental design for a pendant, as shown and described.

Dated this 25th day of June, 1930.

FRITZ SCHULTE.
